UNITED STATES PATENT OFFICE.

EDWARD H. ANGIER, OF FRAMINGHAM, MASSACHUSETTS.

WINDOW CURTAIN.

Application filed January 31, 1922. Serial No. 532,971.

To all whom it may concern:

Be it known that I, EDWARD H. ANGIER, a citizen of the United States, and a resident of Framingham, county of Middlesex, 5 and State of Massachusetts, have invented an Improvement in Window Curtains, of which the following description, in connection with the accompanying drawings, is a specification, like characters on the drawings 10 representing like parts.

This invention relates to window curtains or shades and the object of the invention is to provide a device of this character which, besides possessing the very material advantage of costing but a fraction of the amount required for one made of woven material, possesses other advantages which will appear as the description proceeds. My invention finds a particular application to window 15 shades supported from a spring roller so that they may be drawn for the full length of the window or part way and as an example of my invention I will more particularly describe such a curtain in connection 20 with the illustration thereof in the accompanying drawings, wherein:

Fig. 1 is an elevation of a portion of a window frame provided with a spring roller curtain illustrative of my invention; and 30 Fig. 2 is a fragmentary view of a modified form of material applicable for use in such a curtain.

Referring to the drawings, I there show a spring roller 3 of the usual or any preferred 35 type having the usual end pins 5 mounted in brackets 7 attached to the window casing 9. Secured to the roller 3, conveniently in the usual manner by a row of tacks not necessary to illustrate, is a flexible shade or 40 curtain 11 which may consist of or embody in its construction one or more thicknesses of an irregularly gathered or craped paper and which may be provided at the bottom with the usual stiffening bar 15 for the attachment of a handle. Preferably kraft 45 paper is employed which is strong and readily susceptible to a craping process. In the form of the invention shown two thicknesses of paper are employed which are connected by a layer of suitable lentous adhesive 13 such as mineral pitch.

The craped paper provides a flexible and elastic body portion for the curtain which rolls easily and is not liable to tear as would 55 plain paper. Cloth which is employed for

window shades is quite stiff largely because it is sized or painted or otherwise treated to fill up the interstices resulting from the weaving. A sheet of paper as distinguished from a woven fabric is a uniform felted 60 body without interstices and does not require such stiffening to make it opaque or otherwise uniform in its light modifying qualities. Ordinary paper, however, is comparatively stiff and fragile but when subjected to a craping operation as described 65 is soft and flexible and resistant to tearing as it will give elastically under strain instead of starting to tear.

A curtain presenting to the eye a uniform 70 surface of craped paper is really decorative resembling in effect a popular style of wall paper and corresponding thereto in appearance when used in windows of rooms so papered.

Within the scope of the invention the 75 character of the shade may be variously modified while preserving the essential characteristics in order to provide a more resistant body or one having a desired ornamental appearance or a desired light modifying effect. Thus, colored papers or differently colored papers could be used or a paper having an appearance modified by the 80 associated layer 13 and the paper may be 85 more or less translucent or opaque as desired. In any instance, however, the irregular crappings of the paper layer will increase the 90 opacity if such effect is desired or will break up and modify the rays of light in the manner of ribs or irregularities on well known types of glass so that exhibition of shadows on the curtain will be avoided even although more or less light may be transmitted. In other words a curtain may be provided 95 which although translucent will not be transparent or transpicuous. The presence of an intervening layer of homogenous material such as the pitch 13 will also make for 100 opacity.

It will be readily understood that the 105 material described is very inexpensive as compared with cloth. I will now set forth certain further advantages.

When cloth is employed its upper edge must be tacked to the roller or bar on a line accurately at a right angle to the length of the web because if not so tacked the 110 elasticity of the cloth causes it to roll up askew. No great care is necessary when

tacking one end of the described elastic paper to a spring roller because if the angle is wrong the paper will shape itself to a proper angle by pulling it down once or twice. In other words, if the tacking to the roller is such that the paper has a tendency to swing off to one side when pulled down, it is only necessary to pull it down straight until the usual bottom bar is parallel with the window sill and this causes one side or edge portion to stretch. After one or two such operations the paper will remain stretched in those portions thereof necessary to make the shade hang straight. 10
15 The craping of the paper renders it exceedingly flexible and I have practically demonstrated that it will roll up very evenly and smoothly and when wound up is not liable to slip sidewise so as to form, as cloth often 20 does, a roll convex at one end and concave at the other end. Under certain circumstances I may provide the curtain with longitudinal corrugations 17 as indicated in Fig. 2, causing it to hang straight and roll 25 up evenly with the corrugations nesting in the turns of the roll. The long lines of the corrugations have a decorative effect and in certain applications are desirable to neutralize the more or less transverse lines of 30 the craping and will impart an effect of height and give a room the appearance of being high ceiled and airy.

When cloth is employed for window shades it must be either woven to the right 35 widths for different windows or if cut it must be hemmed to avoid leaving raw edges. Paper as described, however, can be cut or trimmed directly to the right width to pro-

vide a curtain completely covering the window without leaving any unsightly edges. 40

A curtain or shade constructed as shown in Fig. 1 of two sheets of paper with intervening pitch is weather resisting and waterproof. For example, rain driving through the window and striking the outer layer of paper cannot penetrate through the inner layer of pitch 13 and the curtain as a whole is not weakened or disintegrated. 45

Having thus described in detail the particular embodiment of my invention illustrated by way of example in the accompanying drawings, the principles exemplified thereby which I claim as new and desire to secure by Letters Patent I shall express in the following claims. 50

1. In a curtain for windows a support having depending therefrom a sheet of transversely craped paper. 55

2. A window curtain comprising a roller and a bottom bar having extending between them a sheet of transversely craped paper. 60

3. A window shade embodying in its construction as a flexible light modifying element a sheet of craped paper. 65

4. A window shade embodying in its construction as a flexible light modifying element a duplex sheet of craped paper having an intervening flexible coating layer. 70

5. A curtain for windows embodying in its construction a sheet of expansible craped paper of suitable size having a cut or unfinished edge. 75

In testimony whereof, I have signed my name to this specification.

EDWARD H. ANGIER.
